UNITED STATES PATENT OFFICE

WADE H. WINEMAN, OF CHICAGO, ILLINOIS, ASSIGNOR TO SULLIVAN MACHINERY COMPANY, A CORPORATION OF MASSACHUSETTS

FURNACE

Application filed June 13, 1923. Serial No. 645,039.

My invention relates to furnaces, and more particularly to blank heating furnaces. An object of my invention is to provide an improved furnace. Another object of my invention is to provide a blank heating furnace having improved means for discharging the blanks of highest temperature. A further object of my invention is to provide a blank heating furnace having improved means for cooling the blank guides and for preheating the air supply to the burner. These and other objects and advantages of my invention will hereinafter more fully appear.

In the accompanying drawings I have shown for purposes of illustration one form which my invention may assume in practice.

In these drawings,—

Fig. 1 is a central vertical sectional view of my improved blank heating furnace.

Fig. 2 is a transverse sectional view taken substantially on line 2—2 of Fig. 1.

Fig. 3 is a detail sectional view showing the blank discharging mechanism in a different position.

In this illustrative form of my invention I have shown a blank heating furnace, generally designated 1, comprising a metal casing or housing 2 of generally rectangular shape preferably disposed at an angle to the vertical as illustrated and suitably mounted on supporting means, herein legs 3. The casing 2 is herein lined with fire bricks 4 and has a burner, generally designated 5, arranged in the front wall of the casing member adapted to admit a gaseous mixture into a combustion chamber 6, formed by the walls of the furnace, and which is provided with a vent or flue 7 disposed at right angles to the combustion chamber for the escape of the products of combustion.

Suitably secured to the casing, herein by bolts 8, is an angularly disposed metal casting member 9 disposed parallel with the rear wall of the furnace having a groove 10 formed therein, adapted to guide a series of contacting blanks 11, herein in the form of cutter bits, through the combustion chamber, and a chamber 12 cored therein. To the bottom of this chamber cold air is admitted under pressure through a pipe connection 13 so

that it impinges upon the hottest part of the guiding member substantially opposite the burner discharge and thereby keeps the metal at a low temperature and prevents rapid deterioration thereof by excessive heat, at the same time that it tends to keep relatively cool the body portions of the blanks 11 which are protected from direct exposure to the flame of the burner by the member 9.

The air then passes upwardly to the top of the chamber 12, discharging therefrom through a pipe connection 14 herein leading to the burner 5 in such manner as to supply preheated air to the burner, thereby materially improving combustion and effecting a saving in fuel. Oil fuel, or gas of any description, is admitted to the burner 5 through a pipe connection 15 from any suitable source of supply. The flame from the burner is directed onto the blanks at the bottom of the magazine, thereby heating the blanks to the maximum temperature just before they are discharged from the furnace, and then passes upwardly in the flue 7 by means of a natural draft, giving the ends of the other blanks in the member 9 a preliminary heating so that by the time they are in line with the burner discharge a relatively small amount of additional heat is required to bring them up to the desired temperature.

Referring more particularly to the blank discharge mechanism, it will be noted that I have provided a reciprocable plunger or ejector 16 adapted to engage the bottom one of the series of blanks as it passes through an opening 17 in the fire brick 4 and force it out through an opening 18 in the casing 2 of the furnace. This plunger is herein suitably secured to a hook portion 19 formed on a reciprocable rod 20 guided, as at 21, on the casing 2 and having a collar 22 suitably attached thereto at a point intermediate its ends. Pivoted, as at 23, on the rear supporting member 3 is a bell crank 24 having arms 25, 26, respectively, the former being pivotally connected to the collar 22 on the rod 20, herein by a toggle link 27, while the latter is adapted to be pressed downward by the foot of the operator under control of a spring 28 to reciprocate the plunger 16 as desired. If desired, the

plunger may be reciprocated by any suitable power means. It will herein be noted that the blanks frequently vary in length or lie uneven with projecting ends so that they occasionally hang up in such manner as to prevent the lowermost of the blanks from being discharged from the furnace, as indicated at 29 in Fig. 1, on a member 30 disposed over the plunger in a plane parallel therewith. I have herein made the member 30 movable to prevent the blank from sticking and to act as a stripper for preventing the blanks from being carried rearwardly by the plunger 16. A pin 31 is provided which is adapted to cooperate with a slot 32 so that the pin will be engaged by the end of the slot slightly before the plunger reaches the end of its rearward movement, thereby moving the member 30 to the right and permitting the stuck blanks to drop into operative position in line with the opening 18 (see Fig. 3). The stripper member 30 is herein also returned to its initial position by means of a spring 33 disposed between a projection 34 formed thereon and a portion 35 formed integral with the furnace casing 2. The mode of operation of my improved device will be clearly apparent from the description given. With a series of blanks in position in the guiding member and the furnace heated up to the desired temperature, the air under pressure circulated through the chamber 12 will cool the guide and supply preheated air to the burner 5 which will in turn heat the bottommost blanks to a maximum temperature and preheat the upper blanks. Then by pressing down on the lever 26 the plunger 16 is reciprocated, discharging the blanks at a desired speed, the member 30 functioning in each operation of the plunger 40 to prevent the blanks from being carried rearwardly by the plunger 16 and from sticking in the guides.

While I have in this application specifically described one form which my invention may assume in practice, it will be understood that this form of the same is shown for purposes of illustration and that the invention may be modified and embodied in various other forms without departing from its spirit or the scope 50 of the appended claims.

What I claim as new and desire to secure by Letters Patent is:

1. In a blank heating furnace, a heating chamber, guides therein wherein a series of blanks are fed, said guides substantially enclosing parts of the body portions of the blanks to protect the same with only the portions to be worked projecting into said chamber, said guides having a hollow space substantially coextensive with said enclosed parts of the body portions through which fluid may be supplied to cool the same, and means to eject the blanks from said chamber.

2. In a blank heating furnace, a heating chamber, guides therein wherein a series of

aligned superimposed blanks are fed by gravity, said guides providing a longitudinal recess substantially enclosing parts of the body portions of the blanks with only the portions to be worked projecting into said chamber, said guides having a continuous hollow space substantially coextensive with said enclosed parts of the body portion through which fluid may be supplied to cool said blanks, and means to eject the blanks of highest temperature from said chamber.

3. In a blank heating furnace, a heating chamber having a flue, guides carried in said flue and extending into said chamber wherein a series of aligned superimposed blanks are carried, said guides being in continuous contact with the body portions of the blanks over a substantial area to protect the same with only the portions to be worked projecting into said chamber, and means to eject said blanks from said chamber.

4. In a blank heating furnace, a combustion chamber, a burner to admit a gaseous mixture thereto, guides disposed in said chamber wherein blanks are fed downward by gravity, and means formed in said guides whereby the air supply to said burner is preheated while cooling said guides.

5. In a blank heating furnace, a combustion chamber having a burner therein, air cooled guides formed therein wherein a series of blanks are fed, and means for supplying air from one end of said guides to said burner.

6. In a blank heating furnace, a combustion chamber, a burner to admit a gaseous mixture thereto, upright blank guides in said chamber having an air chamber therein, means at the bottom of said chamber for supplying cold air thereto, and means for conducting the air from said last mentioned chamber to said burner.

7. In a blank heating furnace, a combustion chamber, an oil fired burner adapted to admit a gaseous mixture thereto, a guide formed in said chamber wherein a series of blanks are fed by gravity, an air chamber in said guide, and means to admit the preheated air in said chamber to said burner to be used in the combustion of said oil in said furnace.

8. In a blank heating furnace, a combustion chamber having an elongated flue at one end thereof, means to guide a series of gravity fed blanks through said flue and said chamber, and means located at the end of said chamber remote from said flue to direct a flame of burning gaseous mixture on the ends of said blanks in said chamber, said flame preheating said blanks in said flue as it passes upward by natural draft through said flue.

9. In a blank heating furnace, a combustion chamber, means to guide a series of blanks through said chamber, and means to discharge the lower blank including a plunger and a stripper cooperating with and operated by said plunger.

10. In a blank heating furnace, a heating chamber, means to feed a series of blanks through said chamber by gravity, means to eject the lowermost blank from said chamber including a ram, and a blank stripper cooperating with said ram for stripping the blanks therefrom.
11. In a blank heating furnace, a combustion chamber, means to guide a series of blanks through said chamber, means to successively discharge said blanks, stripper mechanism operable in one direction thereby, and resilient means for operating said stripper mechanism in the opposite direction.
12. In a blank heating furnace, a combustion chamber, means to guide a series of blanks through said chamber, means to successively discharge said blanks from said chamber including a reciprocating plunger, a stripper disposed parallel to said plunger, and means for reciprocating said stripper.
13. In a blank heating furnace, a combustion chamber, means to guide a series of blanks through said chamber, means to successively discharge said blanks from said chamber including a reciprocating plunger, a stripper disposed parallel to said plunger, and means for reciprocating said stripper including a slot and pin connection with said plunger.
14. In a blank heating furnace, a combustion chamber, means to guide a series of blanks through said chamber, means to successively discharge said blanks from said chamber including a reciprocating plunger, a stripper disposed parallel to said plunger, and means for reciprocating said stripper including a spring operative to move said stripper in one direction.
15. In a blank heating furnace, a heating chamber having an elongated flue at one end thereof, means for guiding a stack of blanks in an inclined position through said flue and into said chamber by gravity, a burner discharging into said chamber at the end thereof remote from said flue, and means for engaging and ejecting the blanks which have been longest subjected to the heat of said chamber individually from said guiding means.
16. In a blank heating furnace, a heating chamber having an inclined elongated flue at one end thereof, an inclined guide arranged along said flue and extending into said chamber for feeding a stack of blanks thereto by gravity, a burner discharging into said chamber at the end thereof remote from said flue, and a plunger reciprocating in a line perpendicular to said guide for successively engaging and ejecting the lowermost blanks in said stack individually from said chamber.
17. The combination comprising a blank heating furnace having a guide therein adapted to carry a stack of blanks, means for ejecting said blanks from said chamber, and means cooperating directly with said
- ejecting means for preventing said blanks from sticking in said guide.
18. The combination comprising a blank heating furnace having a heating chamber, means to guide a series of gravity fed blanks through said chamber, means for ejecting said blanks from said chamber, and means cooperating directly with said ejecting means for preventing said blanks from sticking in said guiding means.
19. The combination comprising a blank heating furnace having a heating chamber, means to guide a series of gravity fed blanks through said chamber, means for ejecting said blanks from said chamber, and means cooperating directly with and operated by said ejecting means including a reciprocable member for preventing said blanks from sticking in said guiding means.
20. In a blank heating furnace, a combustion chamber, an inclined guide formed in said chamber at one end thereof for guiding a series of blanks therethrough with only their portions to be worked projecting from the guides, and a burner located at the opposite end of said chamber from said guide and discharging in a direction toward said guide whereby the maximum heat is concentrated in the locality of said guide.
21. In a blank heating furnace, a combustion chamber provided with an elongated flue at the top and at one end thereof, an inclined guide in said chamber parallel with said flue for guiding a series of blanks therethrough, and a burner located at the end of said chamber remote from said flue and discharging in a direction toward said guide.
22. In a blank heating furnace, a combustion chamber provided with an inclined surface and an elongated flue at one end thereof, a burner discharging into said chamber at the end thereof remote from said flue, means for guiding a series of superimposed gravity fed blanks along said flue adjacent said surface and into said chamber, and a plunger for successively engaging and ejecting the lowermost blank individually from said chamber.
23. In a blank heating furnace, a combustion chamber having a burner therein, inclined air cooled guides formed therein wherein a series of blanks are fed by gravity, and means for supplying pre-heated air from said guides to said burner.
24. In a blank heating furnace, a combustion chamber, means for guiding a series of gravity fed blanks through said chamber, a plunger for successively engaging and ejecting the lowermost blank of said series individually from said chamber, and stripper means for preventing the blanks from moving rearwardly with said plunger.
25. In a blank heating furnace, a combustion chamber, means for guiding a series of blanks through said chamber, a plunger for

ejecting the lowermost blank of said series from said chamber, and means including a resiliently positioned stripper member co-operating with said plunger for preventing the blanks from moving rearwardly with said plunger.

26. In a blank heating furnace, a combustion chamber, a series of blanks therein, a plunger for ejecting said blanks, a blank stripper cooperating with said plunger, and a lost motion connection between said plunger and stripper.

27. In a blank heating furnace, a combustion chamber having an inclined bottom and an elongated flue at one end thereof, means for guiding a series of inclined blanks along said flue and through said chamber, and a burner disposed at the opposite end of said chamber and discharging longitudinally of said bottom toward said guiding means and blanks.

28. In a blank heating furnace, an inclined combustion chamber provided with an elongated flue at one end thereof and disposed perpendicular thereto, a burner at the opposite end of said chamber discharging toward said flue, means to guide a series of gravity fed blanks along said flue and through said chamber, and means for ejecting the blanks from the lowermost portion of said combustion chamber.

29. In a blank heating furnace, a combustion chamber provided with an elongated flue at one end thereof, means to guide a series of superimposed blanks in a straight line along said flue and through said chamber, a burner at the opposite end of said chamber discharging toward said flue, and means including a plunger reciprocable in line with the lowermost blank for discharging said blank from said chamber.

30. In a blank heating furnace, a combustion chamber provided with an elongated flue at one end thereof, means to guide a series of inclined blanks along said flue and through said chamber, a burner discharging into said chamber at the end thereof remote from said flue, and means including a plunger reciprocable in line with the lowermost blank for ejecting the latter laterally from said chamber.

31. In a blank heating furnace, a combustion chamber having a flue, a series of blanks guided along said flue, a plunger for successively engaging and ejecting the lowermost blank of said series individually from said chamber, and means including a rod disposed parallel with said plunger and cooperating lever mechanism for reciprocating said plunger.

32. The combination comprising a blank heating furnace having a guide adapted to receive a stack of gravity fed blanks, means for successively engaging and ejecting said blanks, and means for preventing the blanks

from sticking in said guide and to strip the same from said ejecting means.

33. In a blank heating furnace, a heating chamber having a series of blanks therein, means for ejecting said blanks from said chamber, and means cooperating directly with said ejecting means for stripping the blanks therefrom.

34. In a blank heating furnace, a heating chamber having a series of blanks therein, means for ejecting said blanks from said chamber, and a blank stripper cooperating directly with said ejecting means and operated by the latter. 75

In testimony whereof I affix my signature. 80
WADE H. WINEMAN.
